SAFETY DOOR OF THE BIPARTING TYPE

George Anderson, Summit, N. J., assignor to Ciba Pharmaceutical Products, Incorporated, Summit, N. J., a corporation of New Jersey

Application April 21, 1945, Serial No. 589,591

8 Claims. (Cl. 20—19)

1

The present invention relates to doors, particularly those of the vertical bi-parting type, and to a safety device therefor.

Industrial type elevator installations—freight elevators and the like—are generally provided with vertically movable bi-parting doors. The door sections are generally guided on vertical guides and are interconnected in mutually counterbalancing relationship. One of the door sections, generally the upper one, is provided with a handle or strap whereby it may be pulled in one or the other direction to open or close the door, the other section being simultaneously actuated due to the aforesaid interconnection.

The closing operation is realized in a single movement, usually terminating in a noisy striking together of the two sections as they meet and engage each other. The resultant concussion is in the nature of a shock to the installation, and the repeated shocks incident to repeated opening and closing of the doors create a serious maintenance problem.

The upper section of bi-parting doors is usually provided with a so-called "flame angle" or "flame-bar," depending from said upper section into overlapping relation with the seam between the two sections when the door is closed. This sealing member, usually required by the insurance companies primarily to prevent fire from spreading from one side of the door to the other, has however proven to be a very great accident hazard since it operates as a cutting knife blade, if ever the operator should be inattentive or negligent and inadvertently insert his hand between the two closing edges of the door.

A primary object of the invention is the embodiment of a door, more particularly of the vertical bi-parting type, wherein the aforesaid hazard is eliminated and wherein incidentally the hard shocks and consequent undue wear caused by slamming the door sections together are also eliminated.

Briefly stated, the invention is based upon the principle of enforcing a two-stage movement, instead of the hitherto conventional single movement, when closing the door, and also forcing the operator to use both hands for the second stage of the two-stage movement, thus preventing him from having a free hand which he could accidentally insert between the closing door sections.

Realization of the object of the invention is achieved, according to the latter, by installing a brake piston arrangement which determines and defines the extent of the first stage of the aforesaid two-stage movement and terminates this

2

stage in a smooth manner free from shock or slamming. The second stage of the movement entails the pushing of a release button by the operator with one hand, thereby "short circuiting" the brake and making it possible to bring the door sections to final closing position with the other hand.

The foregoing sets forth generally the purpose of the invention, a presently-preferred method of reducing the invention to practice, and its various broad features and advantages. Other features and advantages of the invention will be apparent from the following detailed description thereof with reference to the accompanying sheet of drawing.

On the said sheet,

Fig. 1 is a schematic representation in elevation of a relationship of parts according to the present invention, and illustrating more particularly the condition which prevails at the end of the first stage of the door-closing movement;

Fig. 2 is a sectional view taken along line 2—2 of Fig. 1;

Fig. 3 is a sectional view illustrating a second embodiment of the invention, with the parts in their respective positions as the door is being opened;

Fig. 4 is a sectional view corresponding to that of Fig. 3, but showing the parts in their respective positions at the end of the first stage of the two-stage door-closing movement; and

Fig. 5 is a sectional view showing the parts of Figs. 3 and 4 at the end of the second or final stage of the closing movement.

Referring first to the embodiment according to Figs. 1 and 2, the door is diagrammatically illustrated as a vertical bi-parting door, such as may be employed for closing an elevator hatchway opening. The door comprises an upper section 10 and a lower section 11 interconnected in counterbalancing relationship in any suitable and desirable conventional manner, as for example through the medium of a chain and pulley arrangement 12. One end of the chain may be attached to brackets 13 provided on the ends of door section 10, while the other end of the chain may conveniently be secured to the respective lateral extensions of the metallic sill 14 which is mounted at the upper edge of door section 11 as shown. The pulling force necessary to raise or lower the upper section 10 may be applied thereto through the handle 15 or with aid of a similar device such as a strap or the like attached to the door. As the upper section is raised, the lower section 11 is simultaneously lowered, and vice-

versa. Conventional door guides, supports, etc. are employed and are not shown.

A metallic flame bar 16 or the like is secured to the outer side of the door section 10 at the lower edge thereof, in such manner that when the door is closed, the bar overlaps and seals the seam between the door sections, as shown more particularly in Fig. 5 of the drawings. In addition to minimizing fire hazard as above explained, bar 16 also prevents the insertion from the outside of any object between the abutting edges of the door.

In accordance with the embodiment being described, a plurality of brake devices may be mounted preferably on the inside of the door. These brake devices are so contrived that, when the upper door section is pulled down to close the door, positive stopping in smooth and silent manner of the respective door sections at a predetermined distance apart from each other is assured. Thus, it is impossible for the operator's hand to be caught in between the closing door sections. In order to bring the latter into wholly closed or abutting relationship, the operator has to use one hand to actuate a release device and the other hand to effect the final closing movement. Both hands of the operator are thus necessarily positioned elsewhere than between the closing door sections.

Each brake device may conveniently comprise a cylinder 17 secured in place by means of straps or the like as shown. Each cylinder is provided with a reciprocating piston 17a, the piston rod of which extends through the lower end of the cylinder and terminates in a weighted bumper head 18 of any suitable configuration with the terminal portion 19 thereof preferably constituted of felt, rubber or other resilient and noise-absorbing material. The upper end of each cylinder 17 is connected by means of a conduit 19 or the like, to a normally closed bleeder valve release mechanism 20.

This release mechanism may conveniently comprise a valve casing 21 provided with a valve seat which is normally closed by a valve member 22 under the influence of spring 23. Connected with casing 21 as shown is a casing 24 for a flap valve or the like 24a. The upper end of the stem of valve member 22 preferably terminates in a press button 25. In order that button 25 may be depressed from either side of the door section 10, a handle rod 26 may be provided which extends through an opening in the said section in which it is centrally pivoted.

Operation of the device is essentially as follows: When the door is opened, i. e. section 10 is raised, each piston 17a descends in its cylinder 16 by the action of gravity so that when the hatchway is open, the piston rod and bumper head 18 depend to a slight extent below the lower edge of section 10. During the downward movement of piston, flap valve 24a opens to allow air to flow into the cylinder 16. The general relationship of parts at this time is shown in Fig. 3.

Closing of the door takes place, as aforesaid, in two stages of movement. The first stage takes place in the usual way when the upper section 10 is pulled down by handle 15. As the upper section approaches the lower section 11, each head 18 engages sill 14 which is in alignment therewith (see Fig. 4) and each piston 17a is moved upwardly in its cylinder. This causes closing of valves 24a and, valves 22 being spring-closed, the air trapped in the cylinders 16 is compressed

until further downward movement of the section 10 is prevented. At this stage, generally exemplified in Fig. 4, there is a safety distance 26 between sections 10 and 11. The dimensions of the parts may preferably be correlated so that a safety distance 26 of about 2 inches is provided at the end of the first stage of the closing movement.

To start the second part of the closing movement and thereby bring the doors to a full close, the operator has to depress push button 25 whereby the accumulated air pressure in the cylinders 17 is relieved and, consequently, the brake "short circuited." As one hand of the operator then pulls on the handle or strap 15 to close the door, the other hand is forced to keep the release button 25 pushed open and this serves as a check against accidentally placing a hand or fingers between the door edges, regardless of whether the door is closed from the elevator cabin (inside) or corridor side (outside). A handle or strap 15 is, of course, also provided on the outside of the door section 10.

While the embodiment of Figs. 1 and 2 involves two brake devices and a single common release mechanism, use may also be made of but a single brake device located at any suitable point on the upper door section. When but a single brake device is used, the release mechanism is situated directly above the cylinder 16 as shown in Figs. 3, 4 and 5.

It will be understood of course that the foregoing detailed description of presently-preferred embodiments of the invention is essentially intended to be illustrative and not limitative in character. Thus, various minor changes within the spirit and scope of the invention as recited in the appended claims will occur to the expert in the art. For example, alternative means may be provided for effecting depression of button 25 from the outside of the door; the flap valve 24a may be of the ball type; button 25 and flap valve 24 may be combined in one unit; the two cylinders 17 may be combined in one unit; or the whole mechanism comprising cylinder 17 flap valve 24 and buttons 25 may be combined in one preassembled unit to fit in a reset of the door, etc. The invention is manifestly applicable to doors used for closing other openings than elevator hatchway openings and may, for instance, be used for warehouse door openings. It may also be applied to single section doors, such as those commonly used on dumbwaiters and the like.

Having thus disclosed the invention, what is claimed is:

1. A safety door of the bi-parting type and comprising upper and lower door sections which are connected together in counterbalanced relationship and which are vertically movable toward each other for closing the door and away from each other for opening the door, and means mounted on and movable with said upper section and engageable by said lower door section at a point during closing movement of said sections whereby the latter may, in the first instance, be positively maintained spaced apart from each other short of complete closure, and means for releasing said first-named means whereby complete closure may be realized.

2. Brake means for a safety door of vertical bi-parting type, comprising a brake cylinder mounted on the upper section of said door, a piston reciprocable in said cylinder and depending therefrom, a normally closed valve in said

cylinder above said piston, said piston being engageable by the lower section of said door during closing movement thereof, whereby air contained in said cylinder is compressed and said sections are stopped short of complete closure, and means for opening said valve to relieve the resultant compression in said cylinder whereupon complete closure of said door may be realized.

3. Brake means for a safety door of the vertical bi-parting type, comprising a brake cylinder mounted on the upper section of said door, a piston reciprocable in said cylinder and depending therefrom, a normally closed valve in said cylinder above said piston, said piston being engageable by the lower section of said door during closing movement thereof, whereby air contained in said cylinder is compressed and said sections are stopped short of complete closure, means for opening said valve to relieve the resultant compression in said cylinder whereupon complete closure of said door may be realized, and means for actuating said valve opening means from both sides of said door.

4. In a vertical bi-parting door installation in which the door sections are connected together in counterbalanced relationship, means depending from the upper door section and engageable by the lower door section to positively stop said sections short of complete closing engagement, said depending means being releasable for vertical displacement to permit complete closing engagement of said sections, and means for releasing said depending means.

5. In a vertical bi-parting door in which the door sections are connected together in counterbalanced relationship, a plurality of brake cylinders mounted on the upper door section, a piston depending from each cylinder and engageable and movable by the lower door section during closing movement of said door sections, means for holding said pistons against displacement by said lower door section at a point short of complete closure of said door, and means for simultaneously releasing said pistons whereby complete closure may be realized.

6. Brake means for a safety door of the bi-parting type, comprising a brake cylinder mounted on one section of said door, a piston reciprocable in said cylinder and projecting from one end thereof, said piston being engageable by the other section of said door during closing movement thereof, whereby air contained in said cylinder is compressed and said sections are brought to a full stop short of complete closure, a one-way inlet valve for air into said cylinder, said valve being positively closed by pressure exerted thereon from said piston during said closing movement of the door, a normally closed re-

lief valve mounted on said cylinder at the other end thereof, and means for opening said relief valve to relieve the compression established in said cylinder during said closing movement, whereupon complete closure of said door may be realized.

7. Brake means for a safety door of the bi-parting type, comprising a brake cylinder mounted on the upper section of said door, a piston reciprocable in said cylinder and depending therefrom, said piston being engageable by the lower section of said door during closing movement thereof, whereby air contained in said cylinder is compressed and said sections are brought to a full stop short of complete closure, a one-way inlet valve for air into said cylinder, said valve being positively closed by pressure exerted thereon from said piston during said closing movement of the door, a normally closed relief valve mounted on said cylinder at the top thereof, and means for opening said relief valve to relieve the compression established in said cylinder during said closing movement, whereupon complete closure of said door may be realized.

8. Brake means for a safety door of the bi-parting type, comprising a brake cylinder mounted on one section of said door, a piston reciprocable in said cylinder and projecting from one end thereof, said piston being engageable by the other section of said door during closing movement thereof, whereby air contained in said cylinder is compressed and said sections are brought to a full stop short of complete closure, a one-way inlet valve for air into said cylinder, said valve being positively closed by pressure exerted thereon from said piston during said closing movement of the door, a normally closed relief valve mounted on said cylinder at the other end thereof, and means operable from either side of said door for opening said relief valve to relieve the compression established in said cylinder during said closing movement, whereupon complete closure of said door may be realized.
